UNITED STATES PATENT OFFICE.

ELVAH O. BULMAN, OF GRAND RAPIDS, MICHIGAN.

LATCH CONSTRUCTION.

1,383,523.

Specification of Letters Patent.

Patented July 5, 1921.

Application filed December 4, 1918. Serial No. 265,251.

To all whom it may concern:

Be it known that I, ELVAH O. BULMAN, a citizen of the United States of America, residing at Grand Rapids, in the county of Kent and State of Michigan, have invented 5 certain new and useful Improvements in Latch Constructions; and I do hereby declare the following to be a full, clear, and exact description of the invention, such as 10 will enable others skilled in the art to which it appertains to make and use the same.

This invention relates to latches and is particularly concerned with the production of a novel latch construction made entirely 15 from sheet metal and comprising but few parts, all of which may be readily and economically stamped from sheet metal. A further object of the invention is to produce a very novel and artistic strike for the 20 latch proper to engage with. Many other objects and purposes besides those specifically stated at this point, together with novel constructions and arrangements of parts for attaining the same, will appear as the description progresses, reference being had to 25 the accompanying drawing showing a preferred form of latch construction, and in which,

Figure 1 is a horizontal section through 30 a fragment of a door and casing therefor, and through the latch and strike attached, respectively, to said door and casing.

Fig. 2 is a side elevation of a fragment 35 of the door, the latch attached thereto also being shown in side view.

Fig. 3 is a fragmentary longitudinal section through the movable latch member adjacent its pivotal connection to a support.

Fig. 4 is a front view of the latch and 40 strike as they appear in operative relation when attached to a door and casing, and

Fig. 5 is a section, taken on the line 5—5, of Fig. 1.

Like reference characters refer to like 45 parts in the different views of the drawing.

The latch is adapted to be attached at the free vertical edge of a door 1 and the strike with which it engages to an adjacent portion of the door casing or jamb 2. In the 50 construction of the latch a case or housing 3 is pressed from sheet metal, it having, preferably, a more or less rounded top and inwardly extending parallel ends and sides, ears 4 extending from each end of the case 55 through which screws or similar suitable

fastening means may be passed for attaching the case to the door 1.

An opening 5 is made through the top of the case substantially at the middle point thereof, and an opening 6 in the side of the case in alinement with the edge of the door. A latch member 7 passes through opening 5, it being formed from a single piece of sheet metal and provided between its ends with two upstanding ears 8 which lie along- 65 side the inner sides of the sides of the case 3, after which the member 7 is passed through opening 5 and formed into a downturned handle 9. A pin 10 passes through the sides of the case and the ears 8 whereby the member is pivotally connected directly to the case. Adjacent its inner end, the member 7 is formed with a lateral arm 11 which passes through the opening 6 and then turned up and formed into a hook-like catch 12, the 70 same being adapted to pass across the meeting edges of the door and casing or jamb. A spring 13 disposed between the latch member 7 and the case 3 has a tendency to normally elevate the inner end of the latch 80 member, as will be obvious.

The strike with which the latch member is to engage is likewise formed as a case 14 and attaching ears 15, the case being of the same form as the latch case 3. It is formed 85 in its top at one side with an opening 16 through which the catch arm 12 may enter as the door is closed. The metal at the side of the case which is cut to permit the passage of the arm 11 is turned upwardly and 90 inwardly as indicated at 17, and it is with this part 17 that the hook of the catch engages, the rounded end of the hook riding under the part 17 until the inner edge of part 17 is passed. In this manner an automatic engagement of the latch with its strike 95 is made when the door is closed, and it is obvious that disengagement of the catch from the strike may be effected by merely lifting on the handle 9. This is the form that the 100 latch mechanism will have when attached to kitchen cabinets or similar inclosed structures, but when used in connection with screen doors or the like, an arm 18 is connected to the latch member 7, passing 105 through the door and formed with a thumb engaging head 19 at its end, while a handle 20 is secured to the door below and in close proximity to the head. With this construction, the latch may be operated from either 110

side of the door to disengage the same from the strike.

The construction described is very simple, but is particularly effective in operation. There are but few parts, all readily formed from sheet metal at low manufacturing cost. The strike with its case of design similar to the latch case adds greatly to the appearance of the construction. It is of course, to be understood that the latch mechanism described is not absolutely dependent upon the specific strike shown and described, but that the strike may be varied in many respects and still be serviceable. The latch member is supported against loose movement by its attachment to a pivot supported by both sides of the latch case; and altogether, the latch construction is very efficient and serviceable in all respects, and may be commercially produced due to its simplicity of structure and consequent economy of manufacture.

I claim:

1. A latch construction comprising a housing having sides and top and formed from sheet metal, a latch member pivotally mounted on and within the housing, the outer end of said member passing through the top of the housing in a plane below that of the pivot and being formed into a depending handle at a distance from the housing, and the inner end of the latch member having a laterally extending arm passing through a side of the housing and turned up at its free end and formed into a hooked catch, and yielding means within the housing associated with the latch member for normally elevating the inner end thereof.

2. In a construction of the character described, a strike comprising a case having sides and top and adapted to be secured to a door jamb, said case having a portion of one side turned inwardly into the case, substantially as and for the purposes described.

3. In a construction of the character described, a strike comprising a hollow case having a top and parallel inwardly extending sides, said top and one side of the case being provided with connected openings, with the metal from the side of the case being turned inwardly into the case above the openings in the top and side of the case,

substantially as and for the purpose described.

4. In combination, a door, a hollow metal housing connected to the door at the free vertical edge thereof, said housing having an opening in its side nearest the edge of the door, a latch member pivotally mounted on and within the housing and extending from the housing for a distance and then turned downwardly, being provided at its end in front of the pivot with an arm extending through said opening in the side of the housing and across the edge of the door, an upturned catch formed on the end of the arm, a strike attached to the door casing, means for yieldingly holding the inner end of the latch member in upper position whereby said catch automatically engages with the strike when the door is closed, and means for moving the catch to disengage from the strike.

5. In combination, a sheet metal housing having sides, a latch member of sheet metal inserted through the housing and having one end positioned within the housing, ears on the latch member lying alongside the inner sides of the sides of the housing, a pivot pin passing through said ears and sides of the housing, a handle formed at the outer end of the latch member a distance from the housing, a laterally extending arm adjacent the inner end of the latch member and passing through a side of the housing and thence formed into a strike engaging catch, and means within the housing associated with the latch member for yieldingly elevating the inner end of the latch member.

6. In combination, a door, a metal housing connected to the door, a latch member pivotally mounted on and within the housing, said latch member having strike engaging means formed thereon and extending through a side of the housing, and a depending operating handle passing through the top of the housing, a member connected to the latch member and passing through the door, and a thumb engaging head on said member at its free end, substantially as described.

In testimony whereof I affix my signature.

ELVAH O. BULMAN.
